METHOD OF EXTINGUISHING FIRES

Sidney Fraser Barclay, Park Works, Manchester,
England, assignor to General Fire Extinguisher
Company, Providence, R. I., a corporation of
Delaware

Application April 8, 1932, Serial No. 604,125
In Great Britain April 10, 1931

6 Claims. (Cl. 169—4)

This invention relates to the extinguishing of fires involving inflammable liquids which are immiscible with water. The invention has particular reference to such inflammable liquids contained in tanks or vessels but its applications are not restricted thereto.

5 Sprinkler type fire extinguishing installations rely upon the water being spread over the area to be protected in order to smother the flames and drench the material in the area. In the case 10 of inflammable liquids such, for example, as petrol and fuel oil, it is found that the ordinary sprinkler installation is not effective in case of fire due to the rapidity and fierceness of the conflagration, but a certain measure of success is obtainable with inflammable liquids low down in deep tanks where quiet conditions exist above the inflammable liquid if the water can effectively prevent the upflow of the burnt gases and the 15 downflow of air.

20 My invention consists in a method of extinguishing fires of inflammable liquids immiscible with water, in which water is projected on to or into the liquid so as to produce therewith at 25 the liquid surface an emulsion which will not burn.

In the art of emulsification, inflammable liquids which are immiscible with water are commonly classed as oils, whether of vegetable, mineral or animal origin. Such an oil and water 30 form a non-inflammable emulsion when the two are agitated together. The oils of commerce do not ordinarily contain emulsifying agents, and under such circumstances in the emulsions formed 35 the oil is in the dispersed phase, that is scattered as minute isolated droplets throughout the continuous or water phase. Emulsions of this type have heretofore been of little or no commercial value because of lack of permanence, but this 40 characteristic is not a deterrent to the successful practice of my invention because permanence of the emulsion is not of primary importance. If substantially the entire surface of the inflammable liquid is emulsified, that is, if the droplets 45 of oil at the surface are surrounded by water, the emulsion is non-combustible and the fire will be extinguished. Such a non-inflammable emulsion need exist only during the agitation of the liquid.

50 This emulsion may be formed by bombarding the surface of the burning liquid with water from above, or the water may be forcibly introduced to the liquid below its surface to effect the formation of the emulsion at the surface. 55 For the purposes in view, namely the extinguish-

ing of fires, the emulsion need only be provided at the surface of the liquid, and because of this, the fire can be put out with a relatively small quantity of water.

5 My invention further consists in the use of means for facilitating the emulsification by water of the surface of the inflammable liquid when fire occurs. That is, an emulsifying agent may be added to the water which will facilitate the emulsifying action and insure the formation of the desired non-inflammable emulsion. Should there be any question as to the type of emulsion likely to be formed by projecting water into contact with any particular oil, one of the methods of identification common to the art may be employed. I prefer the electrical conductivity method in which two electrodes are immersed at about $\frac{1}{4}$ " to $\frac{1}{8}$ " apart in the emulsion. A current of from 12 to 50 volts is sent through the electrodes and the current flow measured by a 20 milliammeter. If the reading approximates that obtained when the electrodes are immersed in water, then the emulsion contains oil in the dispersed phase, whereas should the reading be much lower than when the electrodes are immersed 25 in water, it indicates that the oil is in the dispersing phase. This method is advantageous because it may be employed during agitation, which is necessary in cases where the emulsion is formed without an emulsifying agent and is very fleeting. 30

35 Apparatus by which my improved method may be practiced is shown in the accompanying drawing but it is merely illustrative and it is intended that the patent shall cover by suitable expression in the appended claims whatever features of patentable novelty exist in the invention disclosed.

40 In the drawing:

Figure 1 is a plan of a tank containing an inflammable liquid with means associated therewith for providing at the surface of such liquid an emulsion of that liquid and water;

Figure 2 is a vertical section, taken as on line 2—2 of Figure 1;

Figure 3 is an elevation of a nozzle adapted to project the water onto the surface of the inflammable liquid in such manner as to form the desired emulsion; and

Figure 4 is a section taken as on line 4—4 of Figure 3.

50 In one convenient application of my invention to a tank 1 containing an inflammable liquid 2, such as petrol for example, I mount sprayer nozzles 3 above the surface of the liquid, the 55

heads being spaced, say about four feet apart. As here shown for illustration, the nozzles 3 are mounted on pipes 4 carried by a frame 5 that is supported on floats 6 above the surface of the liquid. The pipes 4 are each connected to a vertical pipe 7 to which a non-inflammable fluid is conducted by a pipe 8 suitably connected to both the pipe 7 and a fixed pipe 9 to permit the frame 5 and its associated parts to rise and fall with changes in the level of the liquid in the tank.

A sprayer nozzle 3, shown in Figures 3 and 4, preferably has a converging throat 10 leading to a discharge opening 12 of about $\frac{1}{4}$ inch in diameter. The water issues from the opening 12 as a vertical jet and strikes a deflector 14 mounted on the arm 16 above the opening. This deflector is about $1\frac{1}{2}$ inches from the opening and is preferably circular in shape having an abruptly turned down edge or flange 14a which may be serrated if desired. The effect of the deflector is to deflect the water in finely divided jets downward on to the surface of the inflammable liquid in such manner as to form a non-inflammable emulsion therewith.

Connected to the bottom of pipe 7 are other horizontal pipes 18 so arranged as to be submerged in the liquid. These pipes are provided with a multiplicity of discharge openings 20 from which the water may be discharged into contact with the inflammable liquid to form an emulsion. Hand valves 22 and 24 can be set so that either the sprayer nozzles 3, or the pipes 18, or both, may be employed for discharge of the water. The supply for pipe 9 may be hand controlled or automatically controlled as desired.

It will be appreciated that the more highly inflammable the liquid, the greater is the degree of emulsification necessary to reduce it to a condition in which it will not burn. This can be controlled by varying the water pressure and by the use of means for facilitating the emulsification. While no exact rule regarding the relation between pressure and inflammability is known, I have found that generally the water pressure needed bears an inverse ratio to the flash point of the inflammable liquid. For example, transformer oil which flashes at about 350° F. may be readily emulsified with a water pressure as low as 30 pounds, while with gasoline which flashes at about -60° F., the pressure should be about 80 pounds. As a practical guide it may be said that with oils having flash points below 0° F. the water pressure may be 80 pounds or more, with oils flashing between 0° F. and 200° F. the water pressure need be only 50 pounds or more, and with oils which flash above 200° F., 30 pounds or more of water pressure will suffice. In cases of uncertainty all doubt can very easily be removed by a simple test. A small shallow pan of one or two square feet in area may be set beneath a sprayer a distance corresponding to that in the contemplated installation. The oil in question may then be placed in the pan and ignited. The emulsifying effect of water discharged from the sprayer under varying pressures can then be determined and a proper pressure selected for the actual installation.

In the case of fuel oil, I find that the emulsification can be satisfactorily produced by water sprayers immersed in the oil, such as the discharge pipes 18, near the surface so as to produce the non-inflammable emulsion at the surface. For fuel oil, the water pressure employed may be from 30 lbs. per square inch upwards.

The sprayer heads of any particular tank or

the like containing inflammable liquid may be adapted to be brought into operation automatically. They may, for example, be under the control of one or more pilot automatic sprinklers 26 of ordinary type, that is to say, when the latter are brought into operation by fire, the sprayer heads are automatically supplied with water by means of, for example, a flooding valve 28 of known form opened consequent upon the fall in pressure in the water supply pipe 30 to the 10 sprinklers. As an alternative the supply of water to the sprayers may be under hand control, in which case a manually operable valve 32 in another line 9' connected to pipe 9 would be employed. Both forms of supply control are herein 15 illustrated.

I may vary the details of the sprayer, the distributing plates and of the control devices to meet any particular requirements.

I may add any suitable emulsifying agent such as gum arabic to the water although as previously described herein water without such additions may be suitable for my purpose.

It will be noted that my invention does not rely upon the cooling effect of the water or upon the exclusion of air from the liquid surface by the water for its results, which as already explained are due to the emulsification of the liquid by the water and the fact that such emulsions have higher ignition temperatures than the inflammable liquids from which they are made according to the degree of the emulsification, until a point is reached at which the emulsion will not burn.

What I claim is:

1. A method of extinguishing a burning inflammable liquid immiscible with water and capable of forming therewith a liquid-in-water emulsion, which comprises bombarding substantially the entire surface of the liquid with finely divided water in such a manner as to form a non-inflammable emulsion.

2. A method of extinguishing a burning inflammable liquid immiscible with water and capable of forming therewith a liquid-in-water emulsion, which comprises forcibly spraying substantially the entire surface of said liquid with water in such a manner as to form a non-inflammable aqueous emulsion.

3. A method of extinguishing a burning inflammable liquid immiscible with water and capable of forming therewith a liquid-in-water emulsion, which consists in projecting finely divided water into contact with the liquid in such manner as to form at substantially the entire surface thereof an emulsion of said liquid and water in which the liquid is in the dispersed phase.

4. A method of extinguishing a burning inflammable liquid immiscible with water and capable of forming therewith a liquid-in-water emulsion, in which a water sprayer system is used, characterized in this, that the sprayer jets effect such a concentrated bombardment of the whole of the burning surface liquid that such surface liquid is broken up and emulsified to a non-inflammable aqueous emulsion.

5. A method of extinguishing a burning inflammable liquid immiscible with water and capable of forming therewith a liquid-in-water emulsion, which consists in providing a device capable of discharging water as a spray jet, and discharging water from said device into contact with substantially the entire surface of the liquid in such manner as to break up the liquid

and form therewith an emulsion in which the liquid is in the dispersed phase.

6. A method of extinguishing a burning inflammable liquid immiscible with water and capable of forming therewith a liquid-in-water emulsion, which comprises bombarding substan-

tially the entire surface of the liquid with finely divided water containing an emulsifying agent capable of facilitating said liquid-in-water emulsion, in such manner as to form the said emulsion.
